UNITED STATES PATENT OFFICE.

JOHN F. MUIR, OF TOPEKA, KANSAS.

PARCEL OR CASH CARRIER.

SPECIFICATION forming part of Letters Patent No. 373,998, dated November 29, 1887.

Application filed June 15, 1887. Serial No. 241,422. (No model.)

To all whom it may concern:

Be it known that I, JOHN F. MUIR, a citizen of the United States, residing at Topeka, in the county of Shawnee and State of Kansas, have invented certain new and useful Improvements in Mail, Parcel, or Cash Carriers; and I do hereby declare the following to be a full, clear, and exact description of the invention, such as will enable others skilled in the art to 10 which it appertains to make and use the same.

My invention relates to a device for carrying mail to or from a street or sidewalk to a house, or parcels, packages, or cash in business-houses, and is especially designed as an 15 improvement on the devices shown in my application filed March 29, 1887, Serial No. 232,895.

The invention will be hereinafter described, and particularly pointed out in the claims.

20 In the accompanying drawings, which form a part of this specification, Figure 1 is a side view of my improved structure; Fig. 2, a plan; and Fig. 3 is a detail perspective.

Reference being had to the drawings and the 25 letters marked thereon, A B represent posts provided with suitable bases, a, for securing them to the floor or ceiling of a building or other suitable support.

The posts A are made of tubular metal, and 30 to the end of each post is attached a plumber's four-way coupling, b, in the form of a cross. From the horizontal arms of the cross project short studs c d, to which are secured arms e f, which extend out from the posts, and to the 35 bent ends g h are attached one end of coiled springs i k. The opposite ends of the springs are attached to a bar l, which crosses the wire C, and may be bent, slotted, or notched to fit over said wire. To each end of the bar l is attached one end of a cord or other flexible material, m, which at its opposite end is secured to the studs c d, to hold the springs i k and the bar l in working position. The cords arrest 40 the resilient force of the springs on their return to their normal position and avoid any rattling of the springs. They may, however, be dispensed with and the springs allowed to return unchecked, the bar l acting as a guide to keep them in proper position.

50 The wire C, which forms the track for supporting the carrier, passes through an extension, n, attached to the cross on each post, and

is secured to an adjusting-screw, o, for regulating the tension of the wire. The extension n of each post is surmounted by a signal-bell, 55 D, for mail service, but is dispensed with in store service.

E is a horizontal bar which passes through the cross or coupling b, and supports a lever, p, fulcrumed in a slot, q, in the bar. One end 60 of the lever p terminates in a rounded head having a short angular projection, r, for engaging with a loop, s, on the end of the carrier, and the opposite end of the lever terminates in a curved arm, t, and from the arm t projects a pin or stud, u, which extends through an aperture, v, in the bent end w of the bar E and supports a spring, x, for returning and holding the projection r of the lever in position to engage with and hold the loop s of the 70 carrier.

The bar E is moved back by means of a cord, a', and returned to its normal position for engagement with the carrier by a spring, b', which is secured to the rear end of the bar and to the 75 post. From each post projects an arm, c', which extends rearward and is provided with a loop, d', in which is supported a wheel, e', which forms a support for the bar E and a sheave for the cord a'. The force or power of 80 the springs i k is regulated, according to the distance the carrier is to be projected, by an adjustable bolt, f', provided with a head, g', against which the lower end or arm, t, of the lever p strikes for disengaging the carrier. The 85 bar E also carries an arm, h, for striking the bell D.

F is the carrier, which consists of a body, i', and a receptacle, k', for packages or cash, and is supported upon small wheels l' l'.

90 At each end of the body of the carrier is a plate, m', with a slot in it for the wire C to pass through, and a loop, s, for engaging with the lever p on the bar E. The plate m' comes in contact with the bar l for propelling the 95 carrier, and also to arrest its momentum when it returns from the opposite end of the system.

The carrier forms subject-matter of another application for Letters Patent filed herewith, Serial No. 241,243, and need not therefore be 100 more fully described herein.

The operation is as follows: The articles for transportation having been placed in the carrier, the bar E at one end of the device is

drawn back by means of the cord a' until the arm t of the lever p strikes against the head g' of the bolt f' and trips the lever p , thus disengaging the loop s on the carrier, when the resiliency of the springs $i k$, operating upon the carrier through the medium of the bar l and the plate m' on the end of the body of the carrier, will project it across the track. When the carrier reaches the opposite end of the structure, its momentum will be arrested by the springs $i k$ at that end of the structure by the plate m' at the advancing end of the carrier striking against the bar l . The blow of the carrier against the bar l may be cushioned and noise prevented by providing a rubber buffer upon the outer surface of each plate m' .

When the device is set up for use to carry mail from a house to the street or vice versa, the cord attached to the bar E at the house end of the line passes out to the post at the street, as shown in dotted lines, so that the mail-carrier or newsboy may bring the carrier from the house to the street and again return it to the house after having placed mail or newspapers in the carrier.

Having thus fully described my invention, what I claim is—

1. The combination of a post, arms projecting from each side thereof, springs supported by said arms, a cross-bar connecting the springs, a horizontal bar between said arms provided with a tripping-lever, a track, and a carrier, substantially as described.

2. The combination of a post, projecting arms and a horizontal bar supported by said post, springs attached to the forward end of said arms, a cross-bar connecting the springs, a tripping mechanism, flexible connections between the cross-bar and the post for arresting the resiliency of the springs, a track, and a carrier, substantially as described.

3. The combination of a post, a horizontal bar supported by and adapted to move through the post and having a right-angled projection and a slot in its front end, a tripping-lever pivoted in said slot, and a returning-spring for said lever, substantially as described.

4. The combination of a post, a horizontal bar supported by and adapted to move through the post, springs for projecting a carrier, a tripping-lever supported by said bar, and an adjustable bar or bolt for disengaging the tripping-lever and regulating the force of the propelling-springs, substantially as described.

5. The combination of a post, a horizontal bar, an arm carrying a combined anti-friction wheel and a sheave supporting the rear end of the bar, and a cord, and a spring for returning the bar, substantially as described.

In testimony whereof I affix my signature in presence of two witnesses.

JOHN F. MUIR.
